CLAIM

The ornamental design for a nerve stimulator device packaging assembly, as shown and described.

DESCRIPTION

FIG. 1 is an isometric, exploded view of a design for a nerve stimulator device packaging assembly showing my new design.

FIG. 2 is an isometric view of a base tray portion of the nerve stimulator device packaging assembly.

FIG. 3 is a front side view thereof.

FIG. 4 is a back side view thereof.

FIG. 5 is a right side view thereof.

FIG. 6 is a left side view thereof.

FIG. 7 is a top side view thereof.

FIG. 8 is a bottom side view thereof.

FIG. 9 is an isometric view of a retainer cap portion of the nerve stimulator device packaging assembly.

FIG. 10 is a front side view thereof.

FIG. 11 is a back side view thereof.

FIG. 12 is a right side view thereof.

FIG. 13 is a left side view thereof.

FIG. 14 is a top side view thereof; and,

FIG. 15 is a bottom side view thereof.

The broken lines in FIG. 1 disclose the environment of the nerve stimulator device packaging assembly and form no part of the claimed design.
